UNITED STATES PATENT OFFICE

ROBERT MARTIN, OF SPONDON, NEAR DERBY, ENGLAND, ASSIGNOR TO CELANESE CORPORATION OF AMERICA, A CORPORATION OF DELAWARE

APPARATUS FOR HOLDING TEXTILE PACKAGES

Application filed August 9, 1928, Serial No. 298,484, and in Great Britain September 6, 1927.

This invention relates to boards for holding weft pirns, cops or other textile packages.

The object of the present invention is to provide a board capable of withstanding prolonged usage in industry.

The board of the present invention consists of a base or support of relatively thick ply wood (for instance 9 ply) having a number of prongs which penetrate the same at desired intervals and which project upwards from said base or support on the one side and the heads or anchorages of which prongs contact with said base or support on the other side, a backing of ply wood (preferably 3 ply or other relatively thin ply wood) being fixed to said base or support to press against the heads or anchorages of the prongs.

One convenient form of board according to the invention consists of a base or support of 9 ply wood having a number of stout wire clout nails (e. g. of 8 gauge) which penetrate the same at desired intervals and which project upwards from said base or support on the one side and the heads of which nails contact with said base or support on the other side, a backing of 3 ply wood being fixed to said base or support, to press against the heads of the nails, by means of screws or nails.

In a preferred form of the invention we employ, instead of the wire clout nails above referred to, twin wire prongs of hair pin shape having a bridge of loop or angle formation set in a plane at right angles to the plane of the prongs. This bridge of loop or angle formation provides a very convenient and highly useful form of anchorage for the prongs. A board according to such form of the invention may consist of a number of such twin prongs which penetrate a base or support of 9 ply wood at desired intervals and which project through said base or support on the one side, the bridge part of loop or angle formation contacting with or being partially sunk into said base or support on the other side, a backing of 3 ply wood being fixed to the base or support by means of nails (preferably clinched nails) or screws, to press against the bridge of the twin prongs.

The boards of the present invention may

comprise any desired number of prongs. Conveniently they may be constructed with 100 to 200 prongs.

The accompanying drawings serve to illustrate some forms of execution of the invention, it being understood that they are given only by way of example and are in no way limitative.

Figures 1 and 2 show a form of board in which stout wire clout nails are employed for the prongs.

Figure 1 is a sectional elevation of part of the board. Figure 2 is a plan of Figure 1.

Figures 3, 4 and 5 show forms of board in which twin prongs of the character above referred to are employed for the prongs. Figure 3 shows part of the board in sectional elevation whilst Figures 4 and 5 are corresponding fragmentary plan views, Figure 4 illustrating the twin prongs with bridges of loop formation and Figure 5 illustrating them with bridges of angle formation.

Referring to Figures 1 and 2, the board consists of a base or support 1 of 9 ply wood through which a number (for instance 100) of 8 gauge wire clout nails 2 are driven at the desired intervals to project upwards from the base or support 1 on the one side, the heads 3 of the nails 2 contacting with said base or support on the other side. A backing of 3 ply wood 4 is fixed to the underside of the base or support 1 by means of nails 5 which are clinched as shown after nailing. The heads 3 of the nails 2 are by these means firmly held between the base or support 1 and the backing 4.

Referring to Figures 3 and 4, the board shown in these figures consists of a base or support 1 of 9 ply wood through which a number of twin wire prongs 2 (for instance 100 twin wire prongs) are driven to project on the upper side of the base or support 1. Each pair of prongs is formed with a bridge of loop formation 3a which provides a convenient anchorage for the prongs, and the prongs are driven through the base or support 1 with their bridges 3a contacting with the underside of said base or support. A backing of 3 ply wood 4 is fixed to the underside of the base or support 1 by means of nails 100

5 which are clinched as shown after nailing. The bridges of loop formation 3a are tightly held or gripped between the base or support 1 and the backing 4.

- 5 5 Referring to Figure 5, this figure shows in plan part of a board constructed in the same manner as that shown in Figures 3 and 4, similar numerals in Figure 5 indicating corresponding parts in Figure 4. In Figure 5 10 however the twin wire prongs 2 are formed with bridge portions of angle formation 3b instead of loop formation.

What I claim and desire to secure by Letters Patent is:—

- 15 1. A device for holding yarn packages, said device comprising a base member, a plurality of prongs penetrating said base member, anchor members on the prongs adapted to engage the underside of the base member, and a backing member attached to the base member and adapted to secure the said anchor members firmly against the base member.

- 25 2. A device for holding yarn packages, said device comprising a base member, a plurality of twin prongs penetrating the said base member from its underside, anchor members on the prongs adapted to engage the underside of the base member, and a backing member attached to the base member and adapted to secure the said anchor members firmly against the base member.

- 35 3. A device for holding yarn packages, said device comprising a base member, a plurality of twin prongs penetrating the said base member, each twin prong comprising two prongs connected by an anchor member adapted to engage the underside of the base member, and a backing member secured to the base member and engaging the said anchor members.

- 45 4. A device for holding yarn packages, said device comprising a base member, a plurality of twin prongs penetrating the said base member, each twin prong comprising two prongs connected by an anchor member lying in a plane at right angles to the prong and adapted to engage the underside of the base member, and a backing member secured to the base member and engaging the said anchor members.

- 55 5. A device for holding yarn packages, said device comprising a wooden base member; a plurality of twin prongs, penetrating the said base member, anchor members extending between pairs of prongs on the underside of the base member, and a wooden backing member secured to the base member and adapted to secure the said anchor members against the base member.

- 60 6. A device for holding yarn packages, said device comprising a ply wood base, a plurality of prongs penetrating the said base member, anchor members on the prongs adapted to engage the underside of the base

member, and a ply wood backing secured to the base member and engaging the said anchor members.

7. A device for holding yarn packages, said device comprising a ply wood base, a plurality of twin prongs penetrating the said base member, each twin prong comprising two prongs connected by an anchor member lying in a plane at right angles to the prong and adapted to engage the underside of the base member, and a ply wood backing secured to the base member and engaging the said anchor members.

8. A device for holding yarn packages, said device comprising a relatively thick ply wood base, a plurality of twin prongs penetrating the said base member, each twin prong comprising two prongs connected by an anchor member lying in a plane at right angles to the prong and adapted to engage the underside of the base member, and a relatively thin ply wood backing secured to the base member and engaging the said anchor members.

In testimony whereof I have hereunto subscribed my name.

ROBERT MARTIN.
